Inventor
G. PERSSON

UNITED STATES PATENT OFFICE.

GOTTFRID PERSSON, OF SVANGSTA, SWEDEN.

DEVICE FOR SOUNDLESS REVERSING OF THE CARRIAGES OF TYPEWRITERS.

Application filed January 28, 1926, Serial No. 84,445, and in Sweden January 12, 1925.

In most of the typewriters an objectionable ratching noise is produced when the carriage is reversed. This is due to the fact that the teeth of the escapement one after 5 the other contact against the spring actuated pawl which checks the movement of the escapement.

The object of the invention is to eliminate the said noise, which is effected by automatically bringing the pawl by means of a special attachment out of the path of movement of the escapement when the carriage is reversed. This attachment is, contrary to 10 hitherto known constructions, entirely free 15 and independent of the escapement itself.

The invention in the preferred form of details is illustrated in the accompanying drawings, wherein only such elements of a typewriter are shown which are essential for 20 the invention.

In the drawing: Fig. 1 is a rear elevational view of a typewriter, showing the parts in the position when the carriage is travelling in the usual way, that is the automatic release device is in inoperative position, a portion of the frame of the typewriter being broken away. Fig. 2 is a similar view but showing the automatic release device in operative position, the carriage being operated in reverse direction. Figs. 3 and 4 are a lateral view and a front view respectively of the special attachment disconnected.

Similar numerals of reference denote corresponding parts throughout the several 35 views.

Referring to Fig. 1 the toothed rack 1 of the carriage (not shown) is in engagement with a pinion 2 fixed to the axle 3 carrying the escapement 4 and also in engagement 40 with a pinion 5 attached to the pivoted releasing lever 6. The toothed rack 1 is fed step by step in a manner known per se in the direction of the arrow 7 when the typewriter is operative, the escapement 4 being 45 alternately released from engagement with the pawl 8 and checked in its movement by the latter. The pinion 5 is freely rotatable on a pin fixed to the lever 6, and between the pinion and the lever a helical spring 9 (see 50 Fig. 3) is wound round said pin in such a manner that the pinion 5 rotates with a cer-

tain amount of friction which is considerably greater than the friction of the pivot of the lever 6. On account of the friction which influences the free rotation of the pinion 5 the toothed rack 1 when it is moved carries the latter and the lever 6 in the direction of the arrow 7, until the lever abuts against a stop 10, so that the lower free end of the lever 6 is kept out of engagement with a projecting arm of the pawl 8, as shown in Fig. 1.

Fig. 2 shows the releasing device in operative position. When the carriage of the typewriter together with its toothed rack 1 is reversed, that is in the direction of the arrow 11, the pinion 5 on account of the friction due to the spring 9 is carried by the rack in the direction of the arrow 11 and thus the lever 6 will rock about its pivot, 70 until it abuts against the stop 12. The lever 6 is bent at a right angle at its lower end forming the part 13 which cooperates with the projecting arm 14 of the pawl 8 and turns the latter about its pivot 15. By this 75 movement the pawl 8 is brought out of engagement with the escapement 4 and is kept in this position as long as the toothed rack 1 is moved in the direction of the arrow 11. Thus the escapement is rendered to rotate 80 freely and the objectionable noise produced by the repeated contact of the same with the pawl when the carriage is reversed, is completely avoided.

What I claim is:—

1. In a typewriter of the type specified the provision of a rocking lever provided with a pinion in constant engagement with the toothed rack of the carriage, the other free end of said lever adapted to engage an 90 arm projecting from the pawl when the carriage is reversed.

2. In a typewriter of the type specified the provision of a rocking lever, a pin on the one end of the lever, a pinion mounted freely rotatably on said pin, a friction producing helical spring arranged between the pinion and the lever, the other end of the lever bent at right angles, said bent end adapted to actuate an arm projecting from the pawl when the lever is rocked in the one 100 direction.

3. In a typewriter of the type specified the provision of a rocking double-armed lever having at the one end a freely rotatable pinion which is checked in its rotation by friction means and is in constant engagement with the toothed rack of the carriage, the pawl checking the movement of the es-

capement provided with a projecting arm arranged in the path of the other end of the rocking lever.

In testimony whereof I have signed my name to this specification.

GOTTFRID PERSSON.
